Primary Examiner — Cynthia Ramirez*Assistant Examiner* — Tamara L Hahn(74) Attorney, Agent, or Firm — Fox Rothschild LLP(57) CLAIM

The ornamental design for a brush head for electric toothbrush, as shown and described.

DESCRIPTION

FIG. 1 illustrates a perspective view of a brush head for an electric toothbrush.

FIG. 2 illustrates a first side of the brush head.

FIG. 3 illustrates a second side of the brush head.

FIG. 4 illustrates a third side of the brush head.

FIG. 5 illustrates a fourth side of the brush head.

FIG. 6 is a top view of the brush head; and,

FIG. 7 is a bottom view of the brush head.

The broken lines in the drawings depict portions of the brush head for electric toothbrush which form no part of the claimed design.
